Patented Oct. 24, 1911.

2 SHEETS—SHEET 1.

Fig. 1.

A technical line drawing of a mechanical assembly, possibly a pump or valve mechanism. The drawing is labeled with various numbers:

- 1: A vertical plate or frame.
- 2: A circular component on the left.
- 3: A circular component on the left.
- 4: A circular component on the left.
- 5: A circular component at the bottom.
- 6: A circular component at the top.
- 7: A circular component on the left.
- 8: A circular component on the left.
- 9: A circular component at the bottom.
- 10: A vertical ribbed cylinder.
- 11: A circular component at the top.
- 12: A circular component on the right.
- 13: A circular component on the right.
- 14: A circular component at the top.
- 15: A circular component on the right.
- 16: A circular component on the right.
- 17: A circular component on the right.
- 18: A circular component on the right.
- 19: A circular component on the right.
- 20: A circular component at the bottom.
- 21: A circular component on the right.
- 22: A circular component on the right.
- 23: A circular component on the right.
- 24: A circular component at the bottom.
- 25: A circular component at the bottom.

The assembly consists of a central vertical cylinder (10) with a ribbed outer surface. It is mounted on a base (5) with a stepped profile. Various plates, rings, and shafts (1-4, 6-19, 21-25) are attached to the sides and top of the cylinder, forming a complex mechanical structure.

UNITED STATES PATENT OFFICE.

ALBERT MANDERBACH, OF CULBERTSON, MONTANA.

HINGE.

1,006,765.

Specification of Letters Patent. Patented Oct. 24, 1911.

Application filed March 17, 1910. Serial No. 549,936.

To all whom it may concern:

Be it known that I, ALBERT MANDERBACH, a citizen of the United States, residing at Culbertson, in the county of Valley and 5 State of Montana, have invented a new and useful Hinge; and I do hereby declare the following to be a full, clear, and exact description of the invention, such as will enable others skilled in the art to which it 10 appertains to make and use the same.

This invention relates to improvements in door hinges and one of the objects thereof is the provision of a door hinge with a sectional leaf adapted to be adjusted on a suitable support, whereby the hinge can hold a 15 door to a casing having surfaces disposed on a different plane from those of the door.

Another object of the invention is the construction of a spring door hinge having a 20 leaf provided with an integral spring casing a leaf provided with an adjustable attaching portion whereby the leaves may be secured to surfaces in different planes.

With the above and other objects in view 25 the invention comprises certain combinations, constructions and arrangements of parts clearly described in the following specification and clearly illustrated in the accompanying drawings, forming a part of 30 the specification, wherein,

Figure 1 is a cross sectional view showing the improved hinge secured to a door and the casing thereof, Fig. 2 is a front elevation of the door hinge, Fig. 3 is a side elevation thereof, and Fig. 4 is a detail sectional view showing the ratchet and pawl 35 adjustment for the spring of the hinge. Fig. 5 is a detail perspective view of the section 12, showing the posts or guides 20. Fig. 6 is a detail perspective view of the 40 thumb-screw or pin 18.

Referring to the accompanying drawings illustrating the invention 1 denotes a door casing and 2 the door which works in the 45 casing. A hinge leaf section 3 is attached to the door 2, which leaf section is provided with an integral spring casing 4 and with integral pintle holding lugs or arms 5 and 6, located at the ends of said leaf. The ends 50 of the casing 4 are spaced apart from the lugs or arms 5 and 6 to form slots 7 and 8, the slot 7 being of greater width than the slot 8. The lug or arm 5 is formed with an integral pin 9, forming a socket for the 55 reception of the threaded end of the pintle 10, one end of which is provided with a

head 11, formed to mate the head of the pin 9. The pintle extends through an opening in the lug or arm 6 and into the socket of the pin 9, to which it is secured. 60

The second leaf comprises two sections 12 and 13; the section 12 being secured to the door casing 1 by suitable screws and the section 13 being hingedly connected by its pintle engaging lugs or arms 14 and 15 with the pintle 10. The section 13 is provided with three vertically spaced perforated lugs, two lugs 16 being located near the ends of the section 13 and one lug 17 being located midway on said section between the lugs 16. The central lug 17 is provided with internal screw threads for the reception of the thumb screw or pin 18, which is provided with an end 19 swiveled in an opening of the attaching section 12. The section 12 is provided with two fixed posts or guides 20, which work freely through the perforated lugs 16. The lengths of the guide posts 20 and the screw 18 may vary, according to the thickness of the casing, and the guide posts 20 may be riveted in place or threaded to the section 12, as desired. 70

On the pintle 10 a coil spring 21 is positioned, one end of this spring being secured in the recess 22 of the section 13 and the outer end being secured to the tubular extension 23 of the ratchet wheel 24, which wheel is located between the lugs 5 and 15. The ratchet wheel 24 is engaged by a pawl 25 which is secured to the section or leaf 3 so as to be rocked thereon by manual effort. This pawl is adapted to hold the ratchet wheel against movement. The ratchet wheel 24 is provided with a series of circumferentially disposed openings for the 80 reception of a nail or other tool whereby the spring can be tightened. Owing to the slot 7 in the casing it is possible to tighten the spring while the door is closed. 85

The improved door spring is especially 90 useful in attaching screen doors to door casings and renders the usual spacing cleats unnecessary. 95

Having described my invention I claim:—

A hinge comprising in combination a pair 105 of hinge leaves having right angularly disposed perforated arms, a pintle pivotally connecting said leaves, one of said leaves constructed to be attached to a door, the other of said leaves comprising two sections, 110 one section constructed to be attached to a door casing and having inwardly projecting

guide pins, the other of said sections constructed to be adjustably mounted on said guide pins and having an intermediate perforated screw threaded lug and an adjusting screw seated in said lug and having an extended unthreaded reduced portion adapted to be passed through an opening in said door casing section and having lugs adapted to be bent back upon the inner face 10 of said casing section providing a swivel

for said screw, whereby said casing section may be adjusted to different forms of door casings.

In testimony whereof I have signed my name to this specification in the presence of 15 two witnesses.

ALBERT MANDERBACH.
